UNITED STATES PATENT OFFICE.

CALVIN L. HALLADAY, OF SAGINAW, MICHIGAN, ASSIGNOR TO SAGINAW SHEET METAL PARTS CORPORATION, OF SAGINAW, MICHIGAN, A CORPORATION OF MICHIGAN.

TRUNK.

Application filed March 28, 1927. Serial No. 173,839.

This invention relates to trunks made of sheet metal, more particularly storm-proof automobile trunks, adapted to be fastened to baggage racks or other supports.

5 An object is to provide a sheet metal trunk structure with reinforcing and interlocking seams so it can be made economically and rapidly, using only the ordinary equipment of a sheet metal working plant, without expensive dies, presses or forming machines, and it can be easily and quickly assembled without special tools.

Another object is to facilitate fastening the seams by spot-welding or riveting during 15 process of assembling.

A novel reinforced construction for the bottom edges of the trunk is also a feature of the invention, whereby cracking at the bottom seam after prolonged use is prevented.

20 Among the advantages attained by my improvement are the following:

The front and bottom are made in one piece, the back is in one piece, and there are two one-piece ends, all provided with folded edge 25 seams so constructed as to enable the front-bottom member to be assembled with the end members by a simple sliding or telescoping movement, and the back can be added in like manner to complete the trunk body assembly.

30 All seams that are to be spot-welded can by this arrangement be exposed to the terminals of a standard commercial welding machine in a most convenient and accessible manner, avoiding the necessity of using 35 specially designed welding jaws to reach the seams. Lifting, turning or like manipulation and handling of the trunk parts while being welded is also avoided by the method of assembling which my improved construction 40 makes possible.

A further object of the invention is to provide a construction having front and bottom back edges in which no seamed joint is employed as heretofore, and consequently there 45 can be no buckling movement of the metal at those places, causing crystallization and cracking along the bottom edges near the anchor bolts, a defect that frequently develops in trunks having their bottoms set into 50 the side walls and hook-seamed.

My improvement also provides a three-ply anchorage for the holding-down bolts, giving a large reinforced area that distributes the

stress of holding-down over the whole trunk body.

The invention also includes an end wall having a trough-like reinforcing member near its upper edge adapted to drain water to the front and outside the trunk.

With the foregoing and certain other objects in view, which will appear later in the specifications, my invention comprises the devices described and claimed and the equivalents thereof.

In the drawings Fig. 1 is a front view of 65 the trunk with the lid raised, the manner of assembling an end indicated by dotted lines.

Fig. 2 is a perspective view, partly broken away, showing the parts disassembled.

Fig. 3 is a fragmentary cross section on 70 line 3—3 of Fig. 1, showing details of the joints.

Fig. 4 is an enlarged detail on lines 4—4 of Fig. 1.

As is clearly shown in the drawings, the 75 trunk structure comprises a bottom and front wall, the upper edge of which has a horizontally disposed drain ledge with an upwardly extending flange, a back wall having a lid hinged thereto, and end walls, the contiguous 80 upright edges of the end, front and back walls formed with interlocking longitudinal flanges, by which the front-bottom can be assembled with the two ends to form a sub-assembly, and the back can be applied to the 85 sub-assembly, all by endwise sliding in interlocked relation.

Each of the upright end walls 1, 1 has its bottom edge 2 bent inwardly to form a horizontal flange that constitutes a reinforcing 90 plate for the trunk bottom 3. Each end wall has its vertical edges, both front and rear, formed with inwardly projecting flanges that extend from the bottom of the trunk up to the cover. The back edge flange 4 extends 95 the full height of the trunk, and the front edge flange 5 is shorter, the front wall of the trunk being lower than its back wall. Each of the upright flanges 4, 5 is folded inwardly back upon itself to form one channel member of a 100 double seam joint, which unites the upright end wall 1 to the front wall 6 and back wall 7. Each upright end wall has its top edge curved to conform to the shape of the lid, and flanged inwardly to present a smooth edge 105 8, Fig. 4.

A trough-like member 9 is secured by spot-welding, or otherwise, to the inner face of each upright end 1, near its top edge, the trough conforming in shape to the curve of the edge. This member 9 reinforces the end 1 and receives the reinforcing rib of the lid, as will later be explained, and serves as a sloping drain to prevent any water that seeps through underneath the edge of the cover from collecting inside the trunk.

The front and bottom of the trunk are formed in one piece, as shown in Fig. 2. This feature of my invention avoids a well-known defect that has developed in practice with trunks having inset tray bottoms that are seamed to the upright walls. My construction avoids tearing out of the trunk bottom near the ends where the bottom is attached to the trunk rack.

The integral, front and bottom for all ordinary sizes of trunks can be made from stock sizes of sheets, without waste and can be made cheaply and accurately with the equipment and tools of an ordinary sheet metal shop.

The front wall 6 has its upper edge formed with a horizontally disposed offset member or ledge 10, by being bent inwardly and then flanged upwardly, the raw edge at the top being folded inside to present a smooth finish.

The upright flange 11 of the ledge is cut short at each end to permit the end lips 12 of the two drain troughs to register with and rest upon the horizontal ledge 10, so that seepage of water which drains down the trough 9, as above described, will escape across the ledge and be prevented from accumulating in the trunk. The plate 2 at the bottom of side wall 1 keeps the lip 12 of the trough and the ledge 10 in proper position by acting as a stop against the bottom 3 when the front and end walls are assembled.

The upper edge of the upright flange 11 is close to the lid 13 when closed, as shown in detail, Fig. 3, to prevent entrance of dirt.

The front wall 6 has its upright edges 14, 14 folded upon its outer face, as shown in Fig. 2, and they constitute the complementary tongue members of the double-seamed joint that secures the front wall 6 to the end walls 1, 1.

The bottom 3, which as already stated, is in one piece with the front wall, has its rear edge 15 flanged upwardly. It also has flat reinforcing straps 16, 16 secured by welding or otherwise to its inside surface and preferably near each end of the trunk, as indicated by dotted lines in Fig. 2, and in Fig. 3.

The back end of each reinforcing strap 16 is bent upwardly to form a flange 17 extending parallel with the flange 15 on the rear edge of the trunk bottom, and is spaced from it, so the two flanges 15, 17 together form a slot or clip that receives and holds the bottom edge of the back wall 7, as shown in Fig. 3.

The front end of the strap 16 is also flanged upward and secured to the front wall, so as to reduce liability of the metal breaking at that point.

This feature, while forming an important part of my present trunk structure, is also capable of being used in sheet metal trunks of different design, and is, therefore, considered as being in itself patentably novel and is so claimed herein.

The back wall 7 is a flat sheet of metal that has its upright edges 18, 18 folded outwardly to form complementary members of double-seamed joints that unite the end pieces 1, 1 to the back wall 7. The top edge of the back wall is folded rearward and downward, terminating in tubular hinge members 19, and its lower edge is tightly secured between the flange 15 of the trunk bottom and flange 17 of the reinforcing strap by riveting, welding, or in any other suitable manner.

Lid 13 is a sheet of metal hinged at its back edge to the back wall 7. It slopes from back toward the front with increasing curvature, the front edge 20 being flush with the front wall 6 when the lid is closed, as shown in Fig. 3. The back edge of the lid is preferably flanged downwardly and outwardly, overlapping the top edge of the back wall and terminating in complementary tubular hinge members 21, which, together with hinge members 19 on back wall 7, receive the pintle 22 and complete the hinge.

The lid has its front edge formed with an inwardly directed flange 23 that rests upon the sloping ledge 10 of the front wall. The side edges of the lid 13 are folded inward, as shown in Fig. 4, to overlap the flange 24 of a reinforcing rib 25 on the under side of lid 13. The reinforcing rib 25 serves also as a means for keeping the lid joints dust-tight, for it extends down close to the bottom of the drain trough 9 on the end wall 1 when the lid is closed.

A rib or offset 13^a may be formed in the lid 13 to more firmly hold the rib 25 in place.

The trunk can be quickly assembled, without the aid of special tools, in the following manner:

The two end walls 1 are stood upon a floor or bench in the manner indicated in the lower part of Fig. 1. The unitary front and bottom is then assembled with the two sides by interlocking the flanges 5 on ends 1, with flanges 14 on front 6, and pushing the front down, so that the interlocked flanges telescope lengthwise. The bottom 3 comes to rest upon the reinforcing flanges 2. This sub-assembly of front, bottom and ends is taken to the spot-welder. The mounting holes 16^a, which have been previously punched, are aligned by a drift pin. The flanges 2, 2 are spot-welded to the bottom 3, the jaws of the welding machine entering from the back of the trunk, which is open.

The two reinforcing straps 16, 16 are then placed inside the bottom, aligning the mounting holes with a drift pin in the same manner, and the reinforcing strip, bottom and inwardly projecting flange 2 are all welded together into a three-ply anchorage structure. The reinforcing straps 16 are at the same time welded to the front wall 6. The back 7, without cover 13, is then similarly assembled, by means of the two telescoping seams 4, 18, and is pushed down until the top edge of back 7 is flush with the tops of the ends 1. The lower edge of back 7 may or may not bottom at the bottom of the trunk, as shown in Fig. 3, for the reason that the back, being inserted at the front of the up-turned flange 15 and behind the up-turned edges 17 of the reinforcing strips, is welded throughout its length to the flange 15 and is also welded to the up-turned edges 17 of the inside reinforcing strip. It is desirable also to spot-weld the two back seams 4, 18 in several places to prevent the seam from sliding out or being pulled apart.

The foregoing constitute all of the assembling operations on the box itself.

For practical reasons it is advisable to enamel or paint the box and cover separately. Therefore, the cover is assembled later by inserting the hinge rod or pintle 22.

The completed trunk is fixed to the luggage rack of an automobile by means of anchor bolts 26 that pass through the reinforced three-ply part of the bottom near the end 35 walls.

The assembled trunk is dust-proof and storm-proof and rigid to withstand the jolts and stresses that automobile trunks are usually subjected to.

When the lid is closed its inner reinforcing ribs 25 come close to the bottoms of the troughs 9 on the end walls and thus divide the trough into two parts, as if by a lengthwise partition, thereby performing the double function of supporting the lid and serving as baffles to restrict or prevent air circulation into or out from the trunk. The inwardly turned flange 23 takes its seat on the ledge 10 and the upwardly projecting flange 50 11 of the ledge comes up close to the under side of the lid, thus forming a double jamb that prevents air circulation.

If water driven against an end of the trunk, as from a washing hose, gets under the 55 cover it will be stopped by the reinforcing rib 25 on the cover and will run down the trough 9, escaping by crossing the ledge 10. The end lip 12 of the trough and the inner edge of the ledge 10 preferably overlap for 60 that purpose.

Water striking the front of the trunk and getting through the joints formed by ledge 10 and flange 23 will be stopped by the up-standing flange 11.

Water forced against the back wall of the

trunk deflects upward, but can not get inside, because of the downwardly and outwardly projecting hinged flange 19; and water from above will be shed by the other hinged flange 21 on the lid.

The above described construction provides a trunk of unusual strength, but of considerable flexibility.

An automobile trunk that is bolted to a trunk rack at the rear of the tonneau receives 75 its greatest strain from fore-and-aft forces, such as jerks of starting, stopping and erratic application of engine power that causes intermittent jumping of the chassis and more or less violent fore-and-aft jerking of the 80 tonneau and trunk. The trunk structure described herein is adapted to effectively resist stresses of that character, without any tendency for the metal to crystallize and break along the bottom seams.

Having thus described my invention, what I claim and desire to secure by Letters Patent is:

1. A sheet metal trunk having a bottom, a front wall, a back wall having a lid hinged thereto, and end walls, the contiguous upright edges of said end, front, and back walls formed with interlocking longitudinal flanges adapted to be assembled by endwise sliding in interlocked relation, each end wall formed 90 with an inwardly projecting horizontal flange at its lower edge, said flange adapted to underlie the trunk bottom and constituting a reinforcing plate therefor.

2. A trunk having a bottom, a front wall, 100 a back wall and a lid hinged thereto, the back edge of said bottom flanged upwardly, reinforcing straps secured to the inner face of said bottom, the back ends of said straps flanged upwardly, the lower edge of said 105 back wall received between the upright flanges of said straps and bottom, end walls having their upright edges engaged with the respective upright edges of the front and back walls by sliding endwise in interlocked 110 relation therewith, the lower edge of each end wall formed with an inwardly projecting horizontal flange adapted to underlie the trunk bottom and said strap and constituting, together with said inner reinforcing strap, 115 a three-ply anchorage band for said bottom.

3. A sheet metal trunk comprising a bottom, a front wall the upper edge of which has a horizontally disposed ledge with an upwardly extending flange, a back wall having a lid hinged thereto, and end walls, the 120 contiguous upright edges of said end, front, and back walls formed with interlocking longitudinal flanges adapted to be assembled by endwise sliding in interlocked relation, each end wall having near its upper edge a trough-like reinforcing member adapted to drain onto said ledge, an inwardly projecting horizontal flange on the lower edge of each end wall adapted to underlie the trunk bottom, 125 130

constituting a reinforcing plate therefor, and serving also as a stop for locating the end of the trough and the ledge.

4. A trunk having a bottom, a front wall, a back wall and a lid hinged thereto, the back edge of said bottom flanged upwardly, reinforcing straps secured to the inner face of said bottom at the end thereof, the back ends of said straps flanged upwardly, the lower edge of said back wall received between the upright flanges of said straps and bottom, end walls each formed with an inwardly projecting horizontal flange adapted to underlie the trunk bottom and constituting, together with said inner reinforcing strap, a three-ply anchorage band for said bottom.

5. A sheet metal trunk having a bottom, a front wall, a back wall having a lid hinged thereto, and end walls, the contiguous upright edges of said end and back walls formed with interlocking longitudinal flanges adapted to be assembled by endwise sliding in interlocked relation, each end wall formed with an inwardly projecting horizontal flange adapted to underlie the trunk bottom and constituting, together with said inner reinforcing strap, a reinforcing plate therefor.

6. A sheet metal trunk comprising a bottom, a front wall the upper edge of which

has a horizontally disposed ledge with an upwardly extending flange, a back wall having a lid hinged thereto, and end walls, the contiguous upright edges of said end and back walls formed with interlocking longitudinal flanges adapted to be assembled by endwise sliding in interlocked relation, each end wall having near its upper edge a trough-like reinforcing member adapted to drain onto said ledge, an inwardly projecting horizontal flange on the lower edge of each end wall adapted to underlie the trunk bottom, constituting a reinforcing plate therefor.

7. A trunk having a bottom, a front wall, a back wall and a lid hinged thereto, the back edge of said bottom flanged upwardly, reinforcing straps secured to the inner face of said bottom at the end thereof, the back ends of said straps flanged upwardly, the lower edge of said back wall received between the upright flanges of said straps and bottom, end walls, each formed with an inwardly projecting horizontal flange adapted to underlie the trunk bottom and constituting, together with said inner reinforcing strap an anchorage for said bottom.

In testimony whereof, I affix my signature.

CALVIN L. HALLADAY.
